DESIGN FOR A COIN HOLDER

Harry D. Smith, West Henrietta, N. Y.

Application December 31, 1942, Serial No. 109,167

Term of patent 14 years

To all whom it may concern:

Be it known that I, Harry D. Smith, a citizen of the United States, residing at West Henrietta, in the county of Monroe and State of New York, have invented a new, original, and ornamental Design for a Coin Holder, of which the following is a specification, reference is had to the accompanying drawing, forming a part of this specification.

In the drawing:

Figure 4 is a vertical section through the body of the coin holder, an intermediate portion of the body of the coin holder being omitted or broken away.

Figure 5 is a vertical cross section through the top of the body of the coin holder and the cover thereof, the lower portion of the body of the coin holder being omitted.

I claim:

The ornamental design for a coin holder, substantially as shown.

HARRY D. SMITH.
